Primary Examiner — Mitchell I. Siegel(74) *Attorney, Agent, or Firm* — Northstar Law Group; Thomas J. Bassolino(57) **CLAIM**

What is claimed is the ornamental design for a wearable vest with hydration pack, as shown and described.

DESCRIPTION

FIG. 1 is a front perspective view of a wearable vest with hydration pack;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof; and,

FIG. 9 is a front perspective view thereof. Shown in use on an unclaimed person.

The smaller broken lines are representative of conventional stitching. The larger broken lines shown are included for the purpose of illustrating unclaimed subject matter and forms no part of the claimed design.
